UNITED STATES PATENT OFFICE.

KENNETH S. JOHNSON, OF JERSEY CITY, NEW JERSEY, ASSIGNOR TO WESTERN ELECTRIC COMPANY, INCORPORATED, OF NEW YORK, N. Y., A CORPORATION OF NEW YORK.

TELEPHONE-CIRCUIT.

1,293,458.

Specification of Letters Patent.

Patented Feb. 4, 1919.

Application filed August 16, 1917. Serial No. 186,485.

To all whom it may concern:

Be it known that I, KENNETH S. JOHNSON, a citizen of the United States, residing at Jersey City, in the county of Hudson and 5 State of New Jersey, have invented certain new and useful Improvements in Telephone-Circuits, of which the following is a full, clear, concise, and exact description.

This invention relates to circuit arrangements for improving telephonic transmission and is directed more specifically to a circuit arrangement for use at an operator's position or at a subscriber's station.

It is an object of the invention to improve 15 both the efficiency and the quality of the transmission from the telephone set.

In the ordinary operator's telephone set heretofore used, the transmitter is generally included in circuit with the battery, a suitable retardation coil and a primary winding 20 of an induction coil. A condenser is also usually employed in a bridge connected across the transmitter and the primary of the induction coil or is included in series 25 with the primary winding of the induction coil.

In such systems, it has been found that while the condenser serves the useful purpose of preventing a flow of current of constant potential through the primary winding 30 of the induction coil and by its continuous charging and discharging, produces the desired varying current effects in the primary winding, considerable loss in the transmission efficiency results from its use. It has also been found that due to the selective nature of the condenser whereby certain frequencies of current are easily transmitted, while other frequencies are largely 35 suppressed, the quality of the transmission 40 has been somewhat impaired.

In accordance with a feature of this invention, the efficiency and the quality of the transmission are improved by including in 45 circuit with the primary winding of the induction coil, a source of potential independent of the usual battery which supplies the transmission current, in such a manner that it will oppose a drop in potential resulting from the current which is forced 50 through the transmitter by the usual transmission battery. By virtue of this arrangement, the same effect is obtained as would result from the use of a condenser of infinite 55 capacity.

These and other features not specifically mentioned above will more readily appear from the following specification and the annexed drawing in which a figure shows diagrammatically an operator's telephone circuit which embodies the invention. 60

In the accompanying drawing, the primary portion of the operator's circuit is shown as comprising a transmitter 1, an exchange battery 3, and a retardation coil 2, 65 which are connected in the usual manner, and an additional battery 4 included in circuit with primary windings 5, 5 of induction coil 6. The secondary portion of the circuit including the usual receiver 8, and 70 the secondary winding 7 of the induction coil 6, is shown as being connected in the customary manner and is indicated as being adapted for connection, through the agency of a listening key 9 of the usual type, to an 75 ordinary operator's cord circuit A of which only a portion is diagrammatically shown.

It is thought that the invention will be more readily understood from a description 80 of its operation. Assuming that the diaphragm of the transmitter 1 occupies a given position, it will be observed that since the additional source of potential is connected so that it will oppose any drop in potential 85 due to current flowing through the transmitter 1, it will be feasible to employ a battery 4 of such relative proportions that there will be no current flowing through the primary windings 5, 5 of induction coil 6. Under such circumstances, the effect upon the 90 transmission of the telephone circuit would be the same as if the exchange battery 3 were connected across the transmitter 1 and the retardation coil 2, disregarding the remainder of the primary portion of the 95 telephone circuit. Under such conditions the alternating current impedance relations in the primary branch of the operator's circuit are the same as would result from the use of a condenser of infinite capacity which would 100 permit the transmission of currents of all frequencies with equal readiness. However, if it is found to be desirable, battery 4 may be chosen as having such potential as will permit a certain definite amount of current 105 to flow through the primary winding of the coil when the diaphragm of the transmitter 1 occupies the given position.

The vibration of the diaphragm of the transmitter as it is spoken into, causes a 110

variation in the resistance of the transmitter in the usual manner and as a result, a current of a varying nature flows through the primary windings 5, 5 of induction coil 5. Current of a corresponding frequency is thereby induced in the ordinary manner in the secondary winding 7 of the induction coil 6 for transmission through listening key 9 to any subscriber's station to which cord 10 circuit A may be connected.

What is claimed is:

1. A station telephone circuit comprising an induction coil, a primary winding therefor, a transmitter and a retardation coil 15 connected in circuit with said primary winding, and two sources of current having different voltages included in circuit with said primary winding to provide therein a varying current upon the operation of said transmitter.
2. A telephone circuit comprising an induction coil, a retardation coil and two sources of current of different voltages, connected in series with said retardation coil 25 and the primary winding of said induction coil, and a transmitter bridged across said series circuit for varying the current flowing through the primary of said induction coil.
3. A station telephone circuit comprising 30 an induction coil, a primary winding therefor, a transmitter, a retardation coil and a source of current connected to said primary winding, and means included with said primary winding for permitting the unrestricted flow of a periodically varying current of any frequency through said primary winding and for opposing the drop in voltage caused by current flowing through said transmitter from said source of current.
4. A station telephone circuit comprising 40 an induction coil, primary and secondary windings therefor, a transmitter, a retardation coil, and two sources of current of different voltages connected to said primary 45 windings. said transmitter and said retard-

tion coil for inducing and controlling the flow of current in said secondary winding of said induction coil.

5. A primary circuit for an operator's telephone set including a transmitter, a retardation coil, two sources of current of different voltages, and the primary winding of an induction coil arranged for producing in said primary winding a varying current corresponding in frequency with the vibration 55 of the transmitter diaphragm.

6. In a station telephone circuit, the combination of a source of potential, a transmitter, an induction coil, and means opposing the passage of direct current from said source through said induction coil and offering substantially zero impedance to voice currents of any frequency.

7. A telephone circuit comprising an induction coil having a primary winding, a 65 transmitter and a retardation coil connected in circuit with the primary winding, and two sources of current having different voltages included in circuit with the primary winding to provide therein no current flow 70 when the transmitter diaphragm is quiescent and a varying current flow upon the operation of the transmitter.

8. A telephone circuit comprising an induction coil, a primary winding therefor, 75 a transmitter bridged across the primary winding, a retardation coil and a source of current connected to the primary winding, and means included with the primary winding for permitting the unrestricted flow of 80 periodically varying currents of any frequency through the primary winding and for opposing the drop in voltage caused by the current flowing through the transmitter from the source of current.

In witness whereof, I hereunto subscribe my name this 14th day of August, A. D. 1917.

KENNETH S. JOHNSON.
